UNITED STATES PATENT OFFICE

SIMON GISH, OF MAQUOKETA, IOWA

FENCE POST

Application filed August 28, 1928. Serial No. 302,606.

This invention aims to provide a post which will remain securely imbedded in the ground and withstand the assaults of stock, and other impacts, novel means being provided for holding a wire fence securely on the post.

It is within the province of the disclosure to improve generally and to enhance the utility of devices of that type to which the invention appertains.

10 With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

20 In the drawings:—

Figure 1 shows in side elevation, a post constructed in accordance with the invention;

25 Figure 2 is an elevation wherein the post is viewed about at right angles to the showing of Fig. 1;

Figure 3 is a cross section on the line 3—3 of Figure 1;

30 Figure 4 is a longitudinal section in which parts are broken away.

The post 1 may be pointed at its lower end, as shown at 17, and preferably is a metal angle member including flanges 2 and 3, the flange 3 being somewhat wider than the flange 2. In the outer edge 4 of the flange 3 there are transverse seats or notches 5. There is an opening 6 in the flange 3, near to the lower end of the post, and close to the top of the post an opening 7 is formed in the flange 3.

40 A clamping jaw 8, in the form of a rod, extends lengthwise of the flange 3, and across the notches 5. The jaw 8 has an offset arm 9 at its lower end, the arm terminating in finger 10, arranged in approximate parallelism to the jaw 8. On the upper end of the jaw 8 there is a keeper 11 located at right angles to the jaw. The arm 9 can be engaged in the opening 6, with the finger 10 inside the flange 3, the construction being such that

the jaw can be swung back and forth in the direction of the arrow A in Figure 2.

The fence, of course, may be of any desired sort, and its wires 15 extend across the flange 3, and across the seats 5. The jaw 8 is swung up parallel to the flange 3, as in Figure 2, and the keeper 11 on the upper end of the jaw passes through the hole 7 in the flange 3. A nut 12, threaded on the keeper 11, engages the inner surface of the flange 3 and serves to hold the jaw 8 tightly against the outer surface of the flange 3. The keeper 11 and the nut 12 may be referred to as a first tightening device.

55 A second tightening device, in the form of a hook bolt 111, is provided. The head of the hook bolt 111 goes around the jaw 8 at a point between the ends of the jaw, as shown in Figure 3, and the shank of the hook bolt 111 passes through an opening 112 in the flange 3. A nut 14 is threaded on the shank of the hook bolt 111 and cooperates with the inner surface of the flange 3, the hook bolt 111 and the nut 14 forming a second tightening device for drawing the jaw 8 toward the flange 3. When the jaw 8 is drawn toward the flange 3, as shown, for instance, in Figure 3, the wires 15 of the fence are bent a little to form a shoulder 16 that enters the seat 5, the general construction being such that the wires will have practically no movement either up or down or horizontally.

65 By removing the nut 12, the jaw 8 may be released, and by removing the nut 14, the hook bolt 111 may be released, the wires 15 being thereby detached from the post 1 quickly and with little labor.

75 Having thus described the invention, what is claimed is:—

1. In a device of the class described, a post provided in one extreme lateral edge with transverse wire-receiving seats, the opposite extreme lateral edge of the post being smooth, a clamp extended lengthwise of the post and across the seats, means for connecting one end of the clamp pivotally with the post, a tightening device connecting the opposite end of the clamp with the post, and a second tightening device connecting the intermediate portion of the clamp with the 80

post to cause the clamp to kink fence wires into the seats at points remote from the tightening device and said means.

2. A post for wire fences, comprising an angle member including flanges arranged at an angle to each other, one flange being disposed parallel to the wire of the fence, the said one flange being provided with a notch which opens through that extreme lateral edge of the said one flange which is remote from the other flange, a clamp extended lengthwise of the said one flange and across the notch, and means for drawing the clamp toward said one flange to cause the clamp to kink a fence wire into the notch and let the fence wire run out of the notch straight, at the said extreme lateral edge of said one flange.

In testimony that I claim the foregoing as my own, I have hereto affixed my signature.

SIMON GISH.
